Des. 185,842
Patented Aug. 11, 1959

185,842

SPRAYING UNIT

Roy C. Patton, Charlotte, N.C.

Application March 24, 1958, Serial No. 50,140

Term of patent 14 years

(Cl. D14—3)

Des. 185,842

PAGE 2

Fig-3

Fig-5

Fig-4

Figure 1 is a perspective view looking from the front end of the spraying unit with the flanged wheels shown in elevated position embodying my new design;

Figure 2 is a perspective view looking from the rear end of the spraying unit with the flanged wheels shown in elevated position;

Figure 3 is a side elevational view of the spraying unit with the flanged wheels shown lowered for riding on railroad tracks and the small pneumatic wheel at the front end shown in retracted position;

Figure 4 is a front elevational view with the flanged wheels shown in retracted position; and

Figure 5 is a rear elevational view with the flanged wheels shown in track engaging position.

The broken line showing of railroad tracks is for illustrative purposes only.

The dominant features of my design reside in those portions shown in full solid lines.

I claim:

The ornamental design for a spraying unit, substantially as shown and described.
